(57) CLAIM

The ornamental design for cigarette paper case, as shown and described.

DESCRIPTION

FIG. 1.1 is a front view of a cigarette paper case in a closed configuration showing my new design.

FIG. 1.2 is a side view thereof.

FIG. 1.3 is a perspective view thereof in an open configuration.

FIG. 1.4 is another perspective view thereof in an open configuration.

FIG. 1.5 is a front view thereof in an open configuration.

FIG. 1.6 is another perspective view thereof in a closed configuration; and,

FIG. 1.7 is another perspective view thereof in an open configuration.

The broken lines in the figures depict portions of the cigarette paper case that form no part of the claimed design.
